ILLUMINATING FIXTURE

Kaskel P. Kallman, Detroit, Mich., assignor, by
mesne assignments, to Technical Service, In-
corporated, Detroit, Mich., a corporation of
Michigan

Application May 21, 1942, Serial No. 443,933

6 Claims. (Cl. 240—52)

This invention relates to illuminating apparatus and in particular to an upright illuminating fixture which is preferably portable.

One object of this invention is to provide an illuminating fixture which may be transported in separate sections and quickly assembled at the location where it is to be used.

Another object is to provide an illuminating fixture employing fluorescent illuminating tubes supported upon a tubular standard, which in turn is preferably supported upon a shaft or stake driven into the ground.

Another object is to provide an illuminating fixture having a source of illumination upon a detachable head, which in turn rests upon a tubular pillar or standard separable from but sustained by a base, the fixture being kept in an upright position by a stake or shaft driven into the ground, means being provided for passing an electric cable up through the base and pillar or standard to the head carrying the illuminating devices.

Another object is to provide an illuminating fixture as set forth in the preceding objects wherein the fluorescent tubes which constitute the sources of illumination are mounted upon a conical head and are slightly downwardly inclined in order to distribute the light more evenly around the base.

Another object is to provide an illuminating fixture having a hollow head with fluorescent illuminating tubes mounted thereon and with a ballast bracket depending from the top member of the head, thereby conveniently and efficiently mounting the ballast and compensator and their associated connections in close proximity to the illuminating tubes.

Another object is to provide an illuminating fixture as set forth in the preceding objects having a structure which is substantially waterproof and weatherproof so that it may be set up outdoors and may operate efficiently regardless of weather conditions.

In the drawings:

Figure 1 is an elevation of an illuminating fixture according to a preferred embodiment of the invention, with the supporting stake shown extending beneath the ground.

Figure 2 is a top plan view of the illuminating fixture shown in Figure 1.

Figure 3 is a horizontal section through the illuminating head taken along the line 3—3 in Figure 1.

Figure 4 is a horizontal section through the pillar or standard just below the top of the sup-

porting stake, taken along the line 4—4 in Figure 1.

Figure 5 is a horizontal section through the pillar or standard immediately above the base, taken along the line 5—5 in Figure 1.

Figure 6 is a vertical section through the illuminating head taken along the line 6—6 in Figure 1.

Figure 7 is a vertical section through the lower end of the pillar or standard, the base, and the supporting stake, taken along the line 7—7 in Figure 1.

Figure 8 is a vertical section through the illuminating head at right angles to Figure 6 and taken along the line 8—8 in Figure 6.

In general, the illuminating fixture of this invention consists of an illuminating head carrying sources of illumination and detachably mounted upon a tubular pillar or standard, which in turn is seated in a socket in a base. The pillar and illuminating head are mainly held upright by a stake which is driven into the ground and which passes upward through an aperture in the base to a disk at the top of the stake which engages the inner walls of the pillar or standard. Provision is made for passing a cable into the base and up through the pillar or standard past the stake into the illuminating head to the ballast and compensator and thence to the fluorescent tubes mounted on the head and constituting the sources of illumination.

The illuminating head consists of a hollow conical structure terminating in upper and lower plates. The upper plate or top carries a downwardly extending bracket upon which is mounted the compensator and ballast. The lower disk or bottom is provided with a socket into which the upper end of the tubular pillar or standard detachably fits. The cone serves to support the fluorescent illuminating tubes and is preferably inclined downwardly so as to illuminate the ground nearer the base than if the illuminating tubes were precisely vertical. Hitherto, the problem of providing an illuminating fixture for circuses, carnivals, fairs, exhibitions and other similar public assemblages has been difficult. The illuminating fixtures provided by the prior art have been lacking in attractiveness or have involved complicated installation procedure or have lacked proper color or distribution of the light, or have been injurious in their effect upon the eyes.

The present invention, however, provides an illuminating fixture which makes use of fluorescent tubes which give a powerful yet soft illumination distributed over a wide area. The il-

luminating fixture of the present invention is quickly and easily set up or taken down, and is very compact when it is disassembled for transportation or storage.

Referring to the drawings in detail, Figure 1 shows a preferred embodiment of the illuminating fixture as consisting of an illuminating head generally designated 10 and a supporting pillar or standard 11, a base 12, and a supporting stake 13. The stake 13 consists of a shaft (Figure 7) having a point 14 and a reduced diameter top 15 carrying a disk 16 which loosely fits the inner wall 17 of the pillar or standard 11. The disk 16 is provided at its edge with an aperture 18 (Figure 4) through which passes an electric cable 19 for conveying electricity to the illuminating head 10. The stake 13 passes through an aperture 20 in the base 12 and is driven deeply into the ground as far as is necessary, depending upon the height and weight of the particular fixture.

The base 12 is dome-shaped and is provided with a chamber 21 and a downwardly-extending central cup-shaped socket portion 22 having a recess 23 adapted to receive the lower end of the tubular pillar or standard 11 (Figure 7). The base socket 22 is provided with an aperture 24 (Figures 5 and 7), communicating with an aperture 25 in the lower end of the pillar or standard 11 and serving for the passage of an electric cable 26 detachably joined to the cable 19 by the separable connector 27. The cable 26 is preferably buried in a shallow trench so that passers-by will not trip over it. The base 12 may also be buried or left exposed as the user may desire. The illuminating head 10 (Figure 6) is provided with a top 28, a bottom 29, and a cone 30 extending therebetween. The bottom 29 is provided with an upwardly-extending cup-shaped socket portion 31 having a recess 32 adapted to detachably receive the upper end of the pillar or standard 11, and is also provided with an aperture 33 for the passage of an electric cable 34 joined to the electric cable 19 by the separable connector 35. The bottom 29 is in the form of a disk with an annular shoulder 36 to which the cone 30 is secured as at 37. The top 28 is similarly provided with an annular flange 38 to which the upper end of the cone 30 is attached as at 39. The cone 30 is provided with peripherally spaced upper and lower apertures 40 and 41 for the passage of the upper and lower illuminating tube sockets 42 and 43 respectively. The upper end of the cone 30 is also provided with apertures 44, through each of which projects a fuse and circuit breaker 45. The sockets 42 and 43 are secured as at 46 and 47 respectively to the cone 30. Mounted in and extending between the sockets 42 and 43 are fluorescent tubes 48 constituting the sources of illumination. The fluorescent tubes 48 are connected as by the wires 49 and 50 to the ballast 51 and compensator 52 (Figure 8), these being mounted upon a ballast bracket 53 having a flange 54 secured as at 55 to the lower surfaces of the top 28. The ballast bracket 53 is roughly in the form of a trapezoid and is provided with flanges 56 along its vertical edges. Secured as at 57 to one of the flanges 56 is an approximately triangular stiffening bracket 58, the upper edge of which is provided with a flange 59 secured as at 60 to the lower surface of the top 28. The top and bottom 28 and 29 are optionally provided with peripheral flanges 61 and 62 respectively facing toward one another and serving for the attachment of a conical transparent cover 29a if it is desirable or necessary.

to protect the fluorescent tubes 48 from theft or from the elements.

In operation, the illuminating fixture is set up by locating the base 12 at the desired location 5 and then driving the stake 13 through its aperture 20 deeply into the ground, but with the upper end of the stake 13 projecting from the ground a suitable distance. An illuminating cable has previously been installed in a shallow 10 trench and is provided with branches or "pigtails" 26, to which the individual illuminating fixtures are connected and from which they are energized. Before the base 12 is placed in position, the pigtail 26 is inserted through its aperture 15 25.

The separable connector 27 is then brought together, joining the cable 19 within the pillar or standard 11, with the cable 26, after which the pillar or standard 11 is lowered over the disk 16 and stake 13 into the recess 23 in the socket portion 22 of the base 12, the cable 19 passing through the aperture 18 in the disk 16. The illuminating head 10 is then lowered upon the top of the pillar or standard 11, with the latter extending upwardly into the recess 32 in the socket portion 31 of the bottom 29, the separable connector 35 having been assembled just prior to the entry of the pillar 11 into the recess 32 so that the cable 19 is electrically connected to the cable 34 within the illuminating head 10.

The illuminating fixture is then energized by passing electric current through the cables 26, 19 and 34, causing the fluorescent tubes 48 to give forth light and illuminate the areas around the fixture.

When it is desired to disassemble the fixture, the reverse procedure is followed. The head 10 is lifted off the pillar or standard 11 and the connector 35 separated. The tubular pillar or standard 11 is then lifted out of its recess 23 in the base 12 and off the stake 13 and laid to one side, the separable connector 27 being separated at the proper time. The disk 16 is removed from the top of the stake 13, the base 12 is then lifted up along the stake 13 and removed, and the stake 13 itself is withdrawn from the ground. The cable 26 and the main cable (not shown) may then be removed from their trenches and the parts suitably packed and stored or transported.

Thus it will be seen that the present invention provides an illuminating fixture which is attractive in appearance, gives a powerful yet soft light, and which is quickly assembled and disassembled in any desired location. The fixture is substantially waterproof and weatherproof and can be set up at any point merely by following the procedure described above. The various parts of the fixture are self-contained and are quickly set up and taken down and are compactly stored or transported.

While a specific embodiment of the invention has been described and illustrated, it will be understood that various modifications may be made within the scope of the appended claims without departing from the spirit of the invention.

What I claim is:

1. In an illuminating fixture, a hollow tubular standard of uniform cross section, an illuminating head having a socket detachably receiving one portion of said standard and a base having a socket detachably receiving another portion of said standard, an illuminating device mounted on said head, an electrical conductor passing through said standard for energizing said illuminating device, detachable connectors interposed

in said conductors adjacent said head and base to permit quick and easy removal and assembly of the fixture parts and a supporting stake within said standard projecting through said base adapted to extend into the ground, said stake being adapted to align the tubular standard with the base and prevent separation of said connectors.

2. In an illuminating fixture, a hollow tubular standard, an illuminating head having a socket detachably receiving one portion of said standard, a base having a socket detachably receiving another portion of said standard, a fluorescent illuminating tube mounted on said head positioned to direct light downwardly in all directions, an electrical conductor passing through said standard for energizing said fluorescent tube, detachable connectors interposed in said conductor at the points of connection of said standard with said base and head to permit easy and quick assembling and dismantling of the fixture parts and a supporting stake within said standard extending through an opening in said base with its upper concealed end in interlocking engagement with said standard and its other end adapted to extend into the ground.

3. In an illuminating fixture, a hollow tubular standard, an illuminating head having a socket slidably and detachably receiving one portion of said standard, a base having a socket detachably and slidably receiving another portion of said standard, a fluorescent illuminating tube mounted on said head, an electrical conductor passing through said standard into said head for energizing said fluorescent tube, electrical connectors interposed in said conductor adjacent the points of detachable connection between the standard, base and head and a stake projecting through the base adapted to enter the ground, said stake having a portion interfitting with said standard adjacent said base.

4. In an illuminating fixture, a hollow tubular standard, an illuminating head having an inverted cup-shaped socket detachably receiving the upper end of said standard, a base having a cup-shaped socket to slidably and detachably receive the lower end of said standard, an illuminating device on said head, an electric conductor passing through said standard for energizing said illuminating device, detachable electrical connectors interposed in said conductor at the points of connection of said standard with said cup-shaped sockets and a supporting stake partly within said standard and adapted to extend through said base into the ground whereby said standard will be retained in assembled relation with the head and base and said connectors will be prevented from accidental separation, said stake having a spacer member adjacent the upper end engaging the interior of said standard.

nating device, detachable electrical connectors interposed in said conductor at the ends of said standard, and a supporting stake partly within said standard and adapted to extend through said base into the ground said stake having a disc-like member on one end interfitting with the standard to retain the connectors in assembled relation.

5. In an illuminating fixture, a hollow tubular standard of uniform cross section, an illuminating head having a cup-shaped socket detachably receiving the upper end of said standard, a base having a cup-shaped socket of the same circular size as the first socket for detachably receiving the lower end of said standard, an illuminating device on said head, an electrical conductor passing through said standard and terminating at each end thereof, means connecting the conductor for energizing said illuminating device, a detachable connector on the other end of said conductor for connection to a source of current and a supporting stake partly within said standard and adapted to extend through said base into the ground and having an interfitting portion on said stake adapted to retain the standard in the cup-shaped sockets and maintain the electrical connectors in electrical engagement.

6. In an illuminating fixture, a hollow standard, an illuminating head having an inverted cup-shaped socket detachably and slidably receiving the upper end of said standard, a base having a cup-shaped socket detachably and slidably receiving the lower end of said standard, an illuminating device on said head, an electrical conductor passing through said standard for energizing said illuminating device, detachable electrical connectors interposed in said conductor adjacent the points of connection of said standard with said cup-shaped sockets and a supporting stake partly within said standard and adapted to extend through said base into the ground whereby said standard will be retained in assembled relation with the head and base and said connectors will be prevented from accidental separation, said stake having a spacer member adjacent the upper end engaging the interior of said standard.

KASKEL P. KALLMAN.
